His Attorney.

UNITED STATES PATENT OFFICE.

WILLIAM K. RANKIN, OF SCHENECTADY, NEW YORK, ASSIGNOR TO GENERAL ELECTRIC COMPANY, A CORPORATION OF NEW YORK.

SWITCH-OPERATING MECHANISM.

Application filed September 7, 1921. Serial No. 499,111.

To all whom it may concern:

Be it known that I, WILLIAM K. RANKIN, a citizen of the United States, residing at Schenectady, county of Schenectady, State 5 of New York have invented, certain new and useful Improvements in Switch-Operating Mechanisms, of which the following is a specification.

My invention relates to electrical switches 10 and particularly to those switches of a high potential type wherein the movable contacts are enclosed in a vessel and are operated by means external thereto. In many of the oil switches in use at the present time movement 15 of the contacts is effected by means of rods or similar members which extend through the top or walls of the switch vessel and the arrangement is often such that in the opening of the switch the operating rod 20 moves toward the interior of the vessel. In the case of switches carrying considerable current the opening of the circuit causes a high pressure to be developed within the vessel by reason of the vaporization and dis- 25 association of the oil or other liquid in which the contacts are immersed and this pressure acting upon the operating means which passes through the wall of the vessel causes the same to move in a direction to 30 close the switch. If the switch has been tripped open by reason of a short circuit, its automatic reclosing may cause a reestablishment of the short circuit, with the result that the system may be considerably damaged. 35 In high power switches wherein the expulsion of the arc gases from the vessel is retarded and in which there is consequently developed very high pressure the provision of some means to prevent the re- 40 closing of the switch in the manner described is a matter of urgent necessity.

One of the objects of the present invention is to provide means of this character which shall prevent the reclosing of the switch in 45 the manner described not only after the switch has been fully opened but during all stages of the opening operation.

Other objects and advantages will appear 50 from the following description taken in connection with the accompanying drawing wherein Fig. 1 represents a vertical section partly broken away of a switch and operating means embodying my invention, and Fig. 2 is a similar view showing a modification. Referring to Fig. 1, 10 and 11 repre-

sent respectively the stationary and movable switch contacts and 12 a vessel adapted to contain oil or similar insulating fluid in which the contacts 10 and 11 are immersed. In the particular form of switch illustrated, 60 the vessel is constructed to withstand considerable internal pressure and all joints are made tight to prevent oil from being thrown out of the vessel when the switch interrupts a heavy short circuit. In the type of switch 65 here shown there are two stationary contacts and two movable contacts, the latter being carried by an insulating rod 14. Rod 14 is formed at its upper end with an enlarged portion or head 15 which is adapted to move 70 within an operating member 16. This member may, if desired, be tubular in form and is preferably provided at its lower end with an inturned flange 17 arranged to prevent the withdrawal of the head 15. Member 16 75 is pivotally secured at 19 to the lever 20 to which the usual operating means employed in switches of this type is connected. The head 15 is formed with a slot 21 at the bottom of which are two inclined faces 22. 80 Depending from the pivotal connection 19 are two pawls 23 arranged to move outwardly in opposite directions into engagement with teeth 24 formed upon the stationary uprights 25, slots 26 being formed in the member 16 through which the pawls are adapted to move toward this engaging position.

In operation the switch is closed by raising the switch operating lever which through the member 16 and rod 14 lifts the contacts 90 11 into engagement with the stationary contacts 10. In order to open the switch the operating lever is released and the rod 14 falls carrying with it contacts 11. If upon the separation of the contacts sufficient pressure is developed in the vessel 12 to force the rod 14 upwardly, the faces 20 on the pawls will engage the faces of the pawls 23 with the result that the lower ends of the pawls will be forced outwardly through the 100 slots 26 and into engagement with the teeth 24. This will prevent any further upward movement of the contacts 11. The arc, if it has not been extinguished at the time this takes place, will subsequently be extinguished due to an increase in pressure within the vessel 12, or if desired other means may be employed to insure the extinguishing of the arc. 105

It is to be noted that it will be impossible 110

to close the switch by the operating lever if the contacts are locked open by the internal pressure. This is advantageous because if closed before the internal pressure is relieved a second opening of the switch in response to overload would result in the creation of an excessively high pressure within the vessel 2 and its consequent damages.

10 In the modification shown in Fig. 2, means is provided whereby the contacts will be instantly locked against reversal of movement in case the opening movement is halted by the pressure within the vessel. In 15 this form the upper end of the rod 14 is formed with a cup shaped portion 40 within which is adapted to be seated the lower end of the rod 41. Secured to the operating rod 14 by means of links 42 are two brake shoes 43 which are adapted to be forced 20 upwardly against friction surfaces 50 formed on the uprights 25. If desired to prevent any slipping caused by oil which may be thrown onto the friction surfaces 25, these surfaces may be considerably roughened. Pivottally secured at their inner 30 ends to the rod 41 are links 44 which have formed at their outer ends slots 45 which are adapted to receive pins 46 secured to the links 42. Stops 47 formed in the rod 14 serve to limit the upward movement of the links 42.

In operation the switch is closed by raising the rod 41 which operating through the 35 links 44 raises the rod 14 and the movable contacts. During this operation the shoes 43 move slightly away from the surface 50, the links being held against rotation by engagement with stops 47. The shoes themselves are prevented from rotating outwardly toward the friction surfaces 50 by lugs 51 formed thereon which engage the sides of the links 42. During the opening of the switch the rods 41 and 14 fall and the 45 brake shoes ride over the surfaces 50. In case, however, the pressure within the vessel is such that the rod 14 starts to rise, the brake shoes are forced outwardly against the surfaces 50 and any appreciable upward movement is prevented.

50 What I claim as new and desire to secure by Letters Patent of the United States, is,—

1. A switch of the type which comprises a vessel, and cooperating contacts separable 55 within said vessel to draw an arc and where-

in pressure is created at the separation of said contacts which tends to force said contacts together, characterized by the fact that means is provided which will prevent the movement of said contacts under the influence of said pressure to closed position from any position occupied thereby during the opening operation. 60

2. A switch of the type which comprises a vessel adapted to contain an insulating 65 fluid, and cooperating contacts within said vessel adapted to be immersed in said fluid, and wherein pressure is created at the separation of said contacts which tends to force the contacts together, characterized by 70 the fact that there is means operable to prevent the reversal in the movement of the contacts because of such pressure from any position occupied by the same during the opening of the switch. 75

3. An electric switch comprising a vessel, contacts separable within said vessel to draw an arc, operating means for said contacts including a connection extending into said vessel, and movable toward the interior 80 of said vessel to separate said contacts, and means operable to prevent the pressure within said vessel from reversing the motion of said contacts said means being adapted to operate at all stages of the 85 opening operation.

4. In a switch of the type which comprises a vessel, and cooperating contacts separable within said vessel to draw an arc and wherein pressure is created at the separation of said contacts which tends to force said contacts together, characterized by the fact that means is provided which is operable by said pressure to prevent the reclosure of said contacts. 95

5. An electric switch comprising a vessel, contacts separable within said vessel to form an arc, operating means for said contacts including a connection extending into said vessel and movable toward the interior 100 of said vessel to separate said contacts, said operating means being formed with a lost motion connection and means responsive to the lost motion of said connection caused by the pressure created within said vessel at 105 the separation of said contacts to prevent their reclosure.

In witness whereof, I have hereunto set my hand this 6th day of September, 1921.

WILLIAM R. RANKIN.
